TARGET SCORING AID

Henry G. Paulus, Burlington, Vt.

Application November 17, 1948, Serial No. 69,573

5 Claims. (Cl. 33—174)

1

My present invention has for its object the provision of a method of scoring rifle and pistol target firing hits wherein each bullet penetration may be accurately evaluated regardless of the obliteration of the target scoring rings due to concentration of shots at any location on the sheet.

A further object of my invention is to provide a scoring device which may be superposed on a target to visually relocate those portions of scoring lines which may have been eliminated by a cluster of shots by using a superposed member having arcuate lines or edges corresponding to one or more of the target scoring circles and thus remove any doubt as to the correct value of each shot penetrating the target.

Another object of my invention is the provision of a scoring aid wherein a plug gauge cooperates with a selected arc on the aiding element to precisely locate each bullet penetration in respect to the scoring areas of the target.

Still other objects and advantages will become apparent from the following description of the present invention illustrated in the accompanying drawing in which:

Figure 1 is a face view of a ring target showing one form of my invention used for scoring shots in a conventional 50 yard small bore target.

Figure 1a is a plan view of the scoring aid per se.

Figure 2 is an elevational view of a plug gauge for convenient use with the scoring plates comprising my invention.

Figures 3 to 7 are views illustrating various shapes of scoring plates to be used with one form of my invention.

Figure 8 is a bottom view of another form of my invention, and

Figure 9 is a sectional view taken on line 9—9 of Fig. 8.

Similar reference characters in the several drawings indicate similar parts.

In all rifle and pistol target shooting, except where only one shot is fired at a target, it frequently occurs that a grouping of shots creates a number of concentrated holes in the target which may overlap more or less and often eliminate a portion of at least one of the scoring rings printed on the face of the target. This situation makes it difficult to properly credit the rifleman with a correct score since it is left for the score marker to draw conclusions, predicated on his imagination as to where the ring lines should be. It will be appreciated that an arbitrary de-

2

cision becomes quite critical, especially in competitive matches and a great deal of argument may on occasion arise.

Bullets in puncturing a paper target do not as a rule leave a clear cut hole but rather an opening from which the paper is torn having a somewhat jagged circumference. This in turn is surrounded by a larger area the size of the bullet in which the paper is disrupted and more or less shredded, the shreds being pushed backward beyond the plane of the rear side of the sheet. However the target being of paper there is a tendency for these disrupted edges to spring back somewhat into place. But more than this when scores are being recorded several targets may be stacked or a target may be laid face uppermost on a plane surface, such as a table top with the consequent result that the displaced fibers surrounding the shot holes may be pressed back into place with the consequent result that it is difficult to distinguish between the actual periphery of the bullet hole and the center hole first mentioned above. The scoring should be predicated on the area of the bullet hole proper and not on the size of the smaller hole from which the paper was clipped or torn away.

To eliminate any question as to correct evaluation of each shot fired through a target, a plug gauge is used which may be inserted into a bullet hole in question and in cooperation therewith I have provided a number of scoring plates which have means thereon for precisely locating the erstwhile position of the obliterated scoring line in respect to the adjacent extremity of the circumference of the bullet penetration as clearly defined by the plug gauge.

Alternatively I further provide a scoring aid as a unitary structure in which the elements of my invention are combined comprising a transparent disc to which the plug gauge is fixed and on which there are inscribed cooperating scoring arcs corresponding to the several target scoring rings as will later be more fully described.

In Fig. 1 of the drawing I have shown a conventional 50 yard small bore target A upon which there appears a number of bullet penetrations some of which are designated by numeral 10. As in the case with all good marksmen, some of the shots may penetrate the bull's-eye while others may be clear of a ring or "clip it in the clear" while other shots may be clustered as at B, such grouping completely eliminating a portion of a scoring ring such as the line 11, which defines the periphery of that area on the target valued at

nine points. Thus with the arc 12, lying between points 13 and 14, having been removed it will be readily seen that any bullet holes in the eight point arcs which might lie in proximity with the position formerly occupied by arc 12 would be incapable of being precisely scored due to the arbitrary or inaccurate replacement of arc 12 in the imagination of the scorer.

To properly deal with the scoring problem illustrated in Fig. 1, I have shown a plug gauge 15 inserted into the bullet hole to be scored. The gauge 15 (Fig. 2) consists of a cylindrical finger grip 16 and a cylindrical penetrating end 17 of a size and shape smaller than the caliber of the bullet used. Above the tip 17 is a flange 18 of the same diameter as the bullet. Since the actual hole remaining in a paper or cardboard target is of smaller size than the bullet due to contraction of the paper and radial tearing, it is necessary to have the penetrating end of the gauge of less diameter to fit snugly in the perforation while at the same time an adjacent collar or flange will represent the actual size of the bullet. This plug gauge when in position clearly defines the location of the periphery of the bullet as it passed through the target.

For relocation of the arc 12, I have shown in Fig. 1 a generally "D-shaped" scoring plate 18^a and illustrated the latter separately in Fig. 1^a. This plate may be made of any convenient material such as sheet metal or plastic and contains thereon concentric arcuate edges of radii equal to that of three pre-selected scoring rings of the target. In the present illustration the line formed by the edge 19 of the plate will lie coincident with a portion of the bull's eye ring 20, the line of edge 21 with the "ten ring" 22, and the line of edge 23 with the "nine ring" 11. The edge 23 of the scoring plate will thus bridge the gap formed by the shot cluster B and will clearly inform the score marker of the exact location in which the excised arc 12 of the target ring should be.

Since the bullet size flange 18 of plug gauge 15, as shown in Fig. 1, does not quite touch the plate representing arc 12 it is immediately conclusive that the bullet hole in question lies wholly within the eight point area and should be accordingly scored. Should the position of the plug gauge be such that proper alignment of the scoring plate 18^a with its respective target rings would be impossible or if the aligned plate should be tangent with the gauge it would demonstrate conclusively that the bullet hole overlapped or touched the scoring ring and the marksman would be entitled to the score of the higher valued area.

In Figs. 3 to 7 I have illustrated various shapes in which my scoring members may be made in the form of plates. Since the concentric scoring rings of a conventional target progressively increase in equal increments, it will be obvious that the size of the plates shown may be selected for cooperation with any adjacent scoring rings of a target.

Figure 3 shows a scoring plate 24 which is circular in shape and for the purpose of illustration has been shown equal in diameter to the "ten ring" 22.

The plate 25 shown in Fig. 4 presents two 180 degree arcs 26 and 27 for use with scoring rings 22 and 11 respectively. The larger arc having shallow notches 27^a which may vary in depth and as these are cut according to the plug 18 may cooperate therewith for greater accuracy

in determining the position of a bullet hole with reference to the ring printed on the target.

In Fig. 5, the scoring plate 28 is provided with arcuate edges 29, 30 and 31 for use with "ten," "nine" and "eight" rings respectively or this particularly shaped plate can be correctly sized to accommodate any three adjacent scoring rings on the target being used.

Scoring plates 32 and 33 have respective arcuate edges 34 and 35 which can be formed with radii equal to that of the "nine ring," as shown, or any other scoring ring of the target as desired.

It is to be understood that the various scoring plates shown in the drawing are but a few illustrations of the many possible combinations of arcuate edges which may be incorporated in a device within the scope of my present invention.

In Figs. 8 and 9 I have shown the above described features incorporated in a single member for carrying out my method of target scoring. A comparatively thick transparent disc 36 of any suitable plastic material has embedded in its lower face 37 a center pin 38 comprising a plug gauge. The latter has a flange 39 the lower surface of which is flush with the disc bottom 37. It corresponds to the diameter of a bullet and is used the same as the corresponding part 18 of the gauge shown in Fig. 2. A penetrating tip 40 of the gauge protrudes from the bottom of the scoring disc.

Molded or inscribed on the lower surface 37 of the scoring disc are arcuate lines 41, 42, 43, 44 and 45 respectively equal in radius to each of the progressive scoring rings of the target. As will be seen in Fig. 8 these lines are each so positioned as to be tangent to the circumference of the gauge flange 39 and correspond to the arcs of the aforementioned separate gauge plates.

In the operation of the scoring disc shown in Figs. 8 and 9 the tip 40 of the gauge is inserted into the bullet hole to be scored and the disc is then rotated to determine if the proper arcuate line on the transparent material coincides with or lies inside of its corresponding scoring ring on the target. If the line is inside of or coincident with this ring the marksman's shot receives the higher scoring value. On the other hand should the arcuate line fall outside of the scoring ring it then becomes conclusive that the bullet penetration lies wholly within the lower valued area and should be scored accordingly. It will be seen that by inscribing on the bottom of the transparent disc a corresponding arcuate line for each scoring ring of the target used, this form of the device may be used for the accurate scoring of any shot registered on the target.

Thus it will be seen that I have provided a target scoring aid whereby concentrated or clustered shots may be accurately evaluated by the use of a plug gauge and arcuate lines which cooperate to precisely locate the relative positions of a bullet hole and an obliterated portion of an adjacent scoring ring. The precise locating effect of my device removes all doubt as to the correct valuation of each shot fired in competitive marksmanship.

While a preferred form of the invention has been shown and described, it will be understood that variations in details of form may be made without departure from the invention as defined in the appended claims.

I claim:

1. A device for scoring individual hits on a ring target, comprising a bullet hole defining plug, said plug having a penetrating end of less

diameter than the bullet and an adjacent collar of equal diameter to the bullet, a member having arcuate edges corresponding to certain scoring rings on said target, said plug and plate cooperating to locate the true position of the bullet hole and its adjacent scoring ring.

2. A device for aiding in determining the scoring location of bullet holes in a target, comprising a plate having a plurality of arcuate peripheral portions each corresponding to a portion of one of the concentric scoring rings on a target for effecting registration of the plate with a given one of said lines when superposed on the target, and a bullet hole defining plug having a peripheral portion equal in diameter to the bullet cooperating with said plate to accurately determine the relative position between a selected bullet hole and its adjacent scoring ring.

3. A target scoring device comprising a bullet hole defining plug having a peripheral portion equal in diameter to the bullet, a separate plate having at least one arcuate edge corresponding to a scoring ring on said target, said arcuate edge when superposed on its corresponding ring serving to precisely locate said ring relative to said bullet hole defining plug.

4. A target scoring device comprising a bullet hole defining plug having a peripheral portion equal in diameter to the bullet, a separate plate having a plurality of concentric arcuate edges

10

15

30

equal in radius to selected scoring rings on the target, any one of said edges when superposed on its corresponding ring cooperating with said plug to precisely locate said ring relative to the bullet hole.

5. A device for scoring individual hits in a cluster of shots on target which has cut away a portion of a scoring ring by such fire, comprising a bullet hole defining plug having a peripheral portion equal in diameter to the bullet used, a reproducing plate having a rim equal in curvature to said scoring ring for superposing on the target to indicate the true position of the cut away ring portion of the target said plug and plate cooperating to locate the relative positions of the scoring ring and bullet hole.
